A. BECKER.
UNDERFRAME FOR CARS.
APPLICATION FILED MAY 12, 1908.

912,276.

Patented Feb. 16, 1909.

UNITED STATES PATENT OFFICE.

ANTON BECKER, OF COLUMBUS, OHIO, ASSIGNOR TO THE RALSTON STEEL CAR COMPANY, OF COLUMBUS, OHIO.

UNDERFRAME FOR CARS.

No. 912,276.

Specification of Letters Patent.

Patented Feb. 16, 1909.

Application filed May 12, 1908. Serial No. 432,485.

To all whom it may concern:

Be it known that I, ANTON BECKER, of Columbus, in the county of Franklin and State of Ohio, have invented certain new and useful Improvements in Underframes for Cars; and I do hereby declare the following to be a full, clear, and exact description of the invention, such as will enable others skilled in the art to which it appertains to make and use the same.

My invention relates to improvements in underframes for cars, and more particularly for use with cars in which the superstructure is supported upon the pedestals,—such 15 for instance as cabooses.

The object of my present invention is to provide simple and efficient means whereby an underframe comprising a center girder and transverse members, can be readily sup-

20 ported through the medium of devices secured to said transverse members and mounted upon and secured to the car pedestals.

A further object is to construct such an 25 underframe in a manner to effectually support the side sills of the car at points beyond the support of said underframe upon the car pedestals, and to facilitate the supporting of furring strips upon which the car 30 flooring is located.

With these objects in view the invention consists in certain novel features of construction and combinations of parts as hereinafter set forth and pointed out in the 35 claims.

In the accompanying drawings, Figure 1 is a plan view of portion of a car underframe with the cover plate 4 removed embodying my improvements. Fig. 2 is a transverse 40 sectional view, and Fig. 3 is a view on the line $x-x$ of Fig. 2.

1 represents a center girder which may consist of two channel irons spaced apart and having suitable bracing means 2 between them, but so far as my present invention is concerned, this center girder may be 45 differently constructed.

Near respective ends of the frame, transverse members or cross beams 3 are located, 50 and so spaced apart as not to interfere with the car wheels, the pedestals for which are connected with these cross beams as herein-after explained. Each cross beam consists, at respective sides of the center girder, of

two channel iron members secured at their 55 inner ends to the center girder,—for which purpose said cross beam members may be provided with flanges 3^a bolted to the center girder. It is evident that the cross beam members at one side of the center girder 60 co-operate with those of the other side for the purpose of forming the cross beams. A compression plate 4 is secured at its side edges to the respective cross beams and, extending across the center girder, terminates 65 inwardly of the ends of the cross beams. Similarly, a tension plate 5 is disposed under the center girder and is secured at respective sides thereof to the lower flanges of the respective cross beams. The outer 70 ends of the cross beams are provided with depressed seats 6 for the accommodation of side sills 7.

At suitable intervals between the pairs of cross beams above described, other transverse 75 members or cross beams 8 are located and these may consist of diaphragms having lateral flanges and the respective members of each cross-bearer are secured at their inner ends to the center girder and between the 80 members of the latter a brace 9 may be located. This brace 9 and the inner ends of the cross-bearer members are secured in place by means of bolts passing through flanges on 85 said braces and flanges at the inner ends of the cross-bearer members. A top plate 10 extends across the center girder and is secured to the upper flanges of the cross-bearer members. The outer end of each cross-beam 90 is provided with a depressed seat 12, which seats co-operate with the seats 6 of the beams 3, to support the side sills 7. The cross beams 3 and 8 also co-operate in supporting a series of furring strips 13, the upper faces 95 of which align with the upper faces of the side sills for supporting the car flooring.

Inwardly removed from the outer ends of the cross beams 3 and between the separated members composing said beams, a flanged plate 14 is located. This plate is provided 100 at its side edges with flanges 15 which are bolted to the respective cross beams 3 and at its lower edge, a flange 16 is provided. The plate 14 is thus so located that it will be disposed directly over a car pedestal 17 and rests upon a flange 17^a of the latter. The plates 14 thus provide supporting means or connections for the underframe with the ped-

estals. Each plate 14 is provided in its vertical body portion with a series of holes for the accommodation of bolts 18 which serve to secure the same to an upwardly projecting portion 19 of the car pedestal, while the lower flange 16 of each plate is provided with holes for the passage of bolts 20 downwardly into the flange 17^a of the car pedestal.

From this construction and arrangement 10 of parts it will be observed that the under-frame is securely attached to and supported by the car pedestals and that the side sills are supported upon the transverse members outwardly beyond the support of the latter 15 upon the car pedestals.

Having fully described my invention what I claim as new and desire to secure by Letters-Patent, is:—

1. A car underframe comprising a center 20 girder, transverse members and attaching means for a car pedestal secured to said transverse members.

2. A car underframe comprising a center 25 girder, transverse members secured thereto and affording supports for side sills, and plates secured to said transverse members for supporting the underframe upon a car pedestal.

3. A car underframe comprising a center 30 girder, transverse members, and means se-

cured to said transverse members and adapted to be secured to the pedestals of a car.

4. A car underframe comprising a center 35 girder, transverse members provided at their outer extremities with seats for side sills and plates secured to said transverse members at points inwardly removed from said side sill seats and affording means for supporting the underframe upon the pedestals of a car.

5. A car underframe comprising a center 40 girder, cross beams each comprising members spaced apart, and flanged plates secured between said members and affording means for securing the underframe upon the pedestals of a car.

6. A car underframe comprising a center 45 girder, transverse members spaced apart, plates secured between said transverse members, each of said plates having a flange at its lower end, car pedestals to which the 50 flanges at the lower ends of said plates are secured, and fastening means passing through said plate and the car pedestals.

In testimony whereof, I have signed this specification in the presence of two subscribing 55 witnesses.

ANTON BECKER.
